UNITED STATES PATENT OFFICE.

HENRY K. PELL AND HENRY W. PELL, OF ROME, NEW YORK.

WAGON-SPRING.

SPECIFICATION forming part of Letters Patent No. 603,028, dated April 26, 1898.

Application filed September 8, 1897. Serial No. 650,967. (No model.)

To all whom it may concern:

Be it known that we, HENRY K. PELL and HENRY W. PELL, citizens of the United States, residing at Rome, in the county of Oneida 5 and State of New York, have invented a new and useful Wagon-Spring; and we do hereby declare that the following, in connection with the accompanying drawings, is a full, clear, and exact description of the invention.

Our invention relates to three-part elliptic vehicle-springs, in which three semi-elliptic springs are used; and its novelty and utility lie in the form of the springs and the means by which they are secured in position. The 15 connection between the springs is effected at each end by three interlocking caps of peculiar construction fitted to receive the eyes on the ends of the springs. A bolt at each end, passing through the caps and eyes, secures 20 the parts together and clamps the eyes of the center spring between inner extensions on the outer caps, so as to prevent independent motion thereof, the eyes of the outer springs being left free to rotate sufficiently on the bolt 25 within their respective caps. The three caps being clamped by the bolt securely together are practically integral and act as a reinforcement to the bolt, relieving it of strain.

The springs are of a new form, being each 30 formed with a short reverse bend near each end, next the eye, by which when compressed the springs register when horizontal—that is, at the time of greatest longitudinal expansion. By this construction a greater arch for 35 the whole spring is obtained and greater resistance to compression, the wagon-body may be set lower and is made more stable, the eyes at the ends of each spring are in line with the axis of the main plate of the spring, and the 40 end thrust is exerted in the line of greatest resistance with less leverage and strain on the caps and bolts.

Our invention will be understood by reference to the accompanying drawings, in which 45 the same numerals of reference indicate the same parts in all the figures.

Figure I is a perspective view of an elliptic spring, showing my improvements. Fig. II is an enlarged view in perspective of one end 50 of the springs in position in the caps. Fig. III is an elevation showing the caps slightly separated on the bolt. Fig. IV is a corre-

sponding vertical longitudinal section showing the caps and the springs secured in position. Fig. V is a side elevation of the end of 55 an upper spring, enlarged, showing its peculiar form. Fig. VI is a corresponding view of the end of the lower spring. Fig. VII is a view in elevation of the ends of the springs compressed substantially to the horizontal 60 position. Figs. VIII and IX illustrate the preceding form of spring. Fig. X is a diagram illustrating direction of end thrust in a spring of the form shown in Fig. VIII.

In the figures, 1 indicates the upper springs, 65 and 2 the lower, secured by usual means to the head-block 3 on the axle 4 of usual construction. The lower spring 2 is formed at its ends with bends 5 5 and eyes 6 6, and the upper springs 1 1 at their ends with bends 7 7 70 and eyes 8 8.

9 9 are the outer interlocking caps, substantially cylindrical in form, opening inwardly to receive the eyes of the upper springs 1 1 and provided with the inner extensions 10 10, 75 which extend through the end walls 12 12 of the inner cap 11 a short distance into the chamber 13 of said cap 11, as best shown in Figs. III and IV, so that when the parts are assembled and secured in position by means 80 of bolt 14 the eye 6 of the lower spring 2 is gripped securely between said extensions 10 10, while the eyes 8 8 of the upper springs are free to move on the bolt 14 as much as is necessary, as the whole spring is compressed and 85 released. Thus it will be seen that the caps cover over and protect the ends of the springs, and the caps being held securely together without movement they may be on the outside well finished without there being any unsightly working joint, all motion being that 90 of the ends of the springs 1 1 on the bolt 14.

By forming the ends of the springs 2 and 1 1 with the bends 5 and 7 at their respective ends greater strength, stability, and resistance is obtained for springs of given sizes, as may be seen by comparing enlarged Figs. V, VI, and VII to Figs. VIII and IX, which latter illustrate the old form of spring not provided with such bends. In that old form 100 of spring the upper and lower springs reach the horizontal or position of greatest extension before they register—that is, before their centers are forced into the same horizontal

plane—and when they do register, as shown in Fig. IX, they have passed the horizontal position and have been, so to speak, turned wrong side out, allowing the spring-sections 5 to buckle, to break, and the plates to open, the spring then being in danger of breaking and having comparatively little strength to resist vibration and rocking of the wagon-body.

10 Where the springs are made in our peculiar form, they do not reach their horizontal position of greatest extension as quickly as in the old form and a greater force is required to compress them to that position. Therefore our springs of the same size and strength give a greater resistance, are in less danger of being broken, and may be set nearer together than the old form, permitting the wagon-body to be set lower and with less vibration and rocking. It will be noticed that our springs reach the position of greatest extension and register simultaneously.

15 As before stated, by our construction the eyes are in line with the axis of the main 25 plate of each spring, and the line of end thrust is exerted on a line through the center of the bolt with less strain on the connection than in the old form of spring where the line of the end thrust passes outside of the 30 bolt, as indicated by dotted lines in the diagram Fig. X.

Having thus fully described our invention, what we claim, and desire to protect by Letters Patent, is—

- 35 1. In a three-part elliptic wagon-spring, the combination of the three springs, having eyes at their ends, of three interlocking caps for receiving the eyes at each end, and of a bolt for securing the parts in position.
- 40 2. In a three-part elliptic spring, the combination of the three springs, having eyes at their ends, and three interlocking caps substantially cylindrical in form, and opening inwardly to receive the eyes of the springs, and 45 bolts for securing the parts in position.
3. In a three-part wagon-spring, the combination of the three springs, having eyes at their ends, three interlocking caps at each end substantially cylindrical in form and having solid outer faces and openings on their inner faces for receiving the eyes of the springs into their hollow interiors, and bolts extending through said eyes, and interlocking caps for retaining the parts in position.
- 50 55 4. In a three-part wagon-spring, the combination of the three springs, having eyes at their ends, three interlocking caps at each

end for receiving the eyes, the outer caps correspondingly formed with extensions extending inwardly through openings in the inner cap to engage with the eyes of the innerspring, and of bolts for securing said parts in position.

5. In a three-part elliptic spring, the combination of the three springs having eyes at their ends, of three interlocking caps at each end for receiving the eyes of said springs, the inner caps having circular openings through their ends, and the outer caps correspondingly formed with circular extensions extending inwardly through said openings a short distance into the interior of said middle cap to engage with the eyes of the inner spring, and bolts passing through said caps and eyes for securing the parts together.

6. In a three-part elliptic spring, the combination of the three springs having eyes at their ends, of three interlocking caps substantially cylindrical in form, having solid outer faces and cut-outs on their inner faces to receive the eyes of the springs into their 80 hollow interiors, the inner caps having circular openings through their ends, the outer caps correspondingly formed with circular extensions fitting said circular openings and extending inwardly therethrough a short distance into the interior of said middle caps to engage with the eyes of the inner spring and to prevent movement of said spring on the bolts, and of bolts securing the parts together.

7. In combination of a three-part elliptic 90 wagon-spring, the three springs having eyes at both ends of each, said eyes centering on the axis of the main plate of their respective springs, interlocking caps for receiving the eyes, and bolts passing through said caps and 95 eyes.

8. In combination, in a three-part elliptic wagon-spring, the upper springs provided with eyes and formed with short downward bends adjacent to the eyes, the lower spring 100 also provided with eyes on its ends and having short upward bends adjacent to said eyes, interlocking caps for receiving said eyes, and bolts for securing the parts in position.

In witness whereof we have hereunto set 105 our hands, in the presence of two attesting witnesses, at Rome, in the county of Oneida, in the State of New York, this 26th day of July, 1897.

HENRY K. PELL.
